UNITED STATES PATENT OFFICE.

ALBEN E. LUNDELL, OF NEW YORK, N. Y., ASSIGNOR TO WESTERN ELECTRIC COMPANY,
INCORPORATED, OF NEW YORK, N. Y., A CORPORATION OF NEW YORK.

SUBSTATION TELEPHONE SET.

1,232,581.

Specification of Letters Patent. - Patented July 10, 1917.

Application filed January 3, 1916. Serial No. 69,912.

To all whom it may concern:

Be it known that I, ALBEN E. LUNDELL, a citizen of the United States, residing at New York, in the county of Bronx and State of New York, have invented certain new and useful Improvements in Substation Telephone Sets, of which the following is a full, clear, concise, and exact description.

This invention relates to substation telephone sets, and more particularly to substation sets for automatic telephone exchanges.

In substation sets for automatic telephone exchanges it has been customary to provide, in addition to the contact springs through which the talking and ringing circuits are controlled, *e. g.* the switchhook springs, a set of contact springs by means of which impulses may be sent out from the substation for controlling the operation of automatic switches. This has been necessary in order to control the operation of such selector switches by means of a special impulse-sending mechanism rather than by the switchhook.

It is the object of this invention to provide a substation telephone set in which the impulse-sending mechanism controls the switchhook contacts for sending out impulses toward the selector switches.

While the invention is described as applied to a telephone desk stand, it will be obvious that this invention may be embodied in telephone sets of widely varying character. It will be further obvious that instead of the disclosed rotary finger hold calling device, impulse-sending mechanisms of various types may be employed, without departing from the spirit of this invention.

In the drawings, Figure 1 is a side elevation, partly in section, of a telephone set embodying this invention. There is shown in this figure a diagram of a circuit adapted to be operated under the control of the substation set. Fig. 2 is a perspective view of the contact springs and the mechanism for actuating the same.

Upon the removal of a receiver 10 from a switchhook 11, pivoted at 9 to a support 8 within a hollow standard 26, arm 12 of contact spring 13, by engaging a stud 14 of the switchhook, will force the same in an upward direction, whereupon the normally separated contact springs 13, 15 and 16 will make contact. The contact springs are mounted on but are insulated from support

8. A line circuit is established from ground-ed battery, through the right-hand winding of a relay 17, conductor 18, transmitter 19, conductor 20, contact springs 13 and 15, conductor 21, the primary winding of an induction coil 22, and the left-hand winding of relay 17 to ground. Relay 17 becomes energized. Receiver 10 is inductively connected with the transmitter circuit through the secondary winding of induction coil 22, 65 conductors 23 and 24, spring 16, and the condenser.

The subscriber may now proceed to operate relay 17 in accordance with the numerical designation of the called line, by actuating an impulse-sending device 25 fastened in any desirable manner to standard 26 of the desk stand. He will insert his finger in a hold, such as 27, through which the numeral representing the desired digit 75 appears, said numeral being indicated on a plate 28 located behind plate 29, on which the finger holds are provided. Dial 29 is fastened to a rotatable shaft 30, and plate 28 to frame 41 of the calling device. Fastened to shaft 30 behind plate 28, are an impulse wheel 31 and a gear wheel 32. The subscriber rotates plate 29 and therefore shaft 30 and wheels 31 and 32 in a clockwise direction until his finger reaches a stop 33. 80 The teeth 34 of wheel 31 engage an arm 35 of a pawl 36 pivoted at 37, to support 8 and projecting through an opening of standard 26, and cause thus an insulated stud 39 carried by arm 38 to move away from arm 40 of contact spring 13 without disturbing the contact between springs 13 and 15. Gear wheel 32 drives, by means of a gearing arrangement 50, a governor 51. This governor, however, does not control the speed 85 of rotation of the devices during the clockwise movement thereof. During the forward movement of dial 29, a motor spring 52, one end of which is fastened to shaft 30 and the other end to plate 28, is wound 90 up, and when the user releases the dial 29, motor spring 52 carries the shaft 30 and the members 29, 31 and 32 fastened thereto, back to normal. The teeth 34 of wheel 31 press arm 35 of pawl 36 downwardly, whereby stud 39 of arm 28 of this pawl will be moved against arm 40 of spring 13 forcing this arm away from contact spring 15. The circuit of relay 17 will thus be broken, and the desired number of impulses transmitted, 105 110

there being provided one tooth 24 for each finger hold 27. During the backward movement of shaft 30, its speed of rotation is controlled by governor 51 in the well-known manner. During the actuation of contact spring 13, springs 15 and 16 are also actuated. Springs 15 and 16 are brought into engagement after and are separated before springs 13 and 15 make contact, and therefore, the subscriber will get no objectionable clicks in his receiver.

What is claimed is:

1. In a telephone set, a transmitter and a receiver, three contact springs for controlling the circuits of said receiver and transmitter, and an impulse-sending mechanism for variably operating said contact springs.
2. A telephone set comprising a transmitter circuit, a receiver circuit inductively con-

nected therewith, a contact in each of said circuits, a switchhook for controlling said contacts, and an impulse-sending mechanism for successively actuating said contacts.

3. A telephone set comprising a transmitter circuit, a receiver circuit inductively connected therewith, a contact in each of said circuits, a switchhook for controlling said contacts, and an impulse-sending mechanism adapted to open first the contact in the receiver circuit and then the contact in the transmitter circuit, and close first the contact in the transmitter circuit and then the contact and the receiver circuit.

In witness whereof, I hereunto subscribe my name this 31st day of December, A. D. 35 1915.

ALBEN E. LUNDELL.
